[57] ABSTRACT

A hollow, conically shaped plate which fastens about

the stake and stake rope anchor section of a camper tent, so as to prevent both children and adults from injury caused by their walking inadvertently into, or tripping over, the tent stake. The unit may be fabricated of a plastic sheet or molding which is impregnated, or painted over, with fluorescent material.

The device is in the general form of a slotted hollow conical section, with the slot permitting the device to be passed over the stake rope, when fastening to a tent stake. Means are provided for fastening an inside surface of the device to the tent stake, and the corresponding outer surface of the device is recessed to permit the stacking of several of these units, when stored.

6 Claims, 5 Drawing Figures

TENT STAKE GUARD

SUMMARY OF THE INVENTION

This invention relates to a guard device for shielding the stake of a tent from passers-by and particularly to a conical-shaped unit that is mounted about the tent stake.

An advantage of this invention is that the device is readily fastened to the stake of a tent so as to form a shield of high visibility about both the tent stake and the anchor section of the attached tent rope. The device may be fabricated of plastic material impregnated or coated with fluorescent pigment or light-reflective material so as to stand out visually at night when illuminated by the beams of a flashlight or other light source.

The device is readily stored and transported, being of light weight and shaped so as to be stackable.

BRIEF DESCRIPTION OF THE DRAWINGS

The objects and features of the invention may be understood with reference to the following detailed description of an illustrative embodiment of the invention, taken together with the accompanying drawings in which:

FIG. 1 is an elevation view of the device;

FIG. 2 is a sectional view of the device taken along line 2—2 of FIG. 1;

FIG. 3 is a plan view of the device;

FIG. 4 is a sectional view of the device, with the device mounted about a tent stake; and

FIG. 5 is a sectional view of the device mounted in an alternate fashion about a tent stake.

DESCRIPTION OF THE PREFERRED EMBODIMENT

Turning now descriptively to the drawings, in which similar reference characters denote similar elements throughout the several views, FIG. 1-4 illustrate the stake guard device 10 which may be formed of a skin 11 of soft plastic material in the shape of a hollow frustum of a truncated cone, with a slot 12 running axially along one side of the device, so as to permit the stake guard 10 to be mounted about a tent stake 21 to which a tent rope 22 is fastened, as shown in FIG. 4.

The interior of the device is fitted at one lower section with reinforcements 18 adjoining a pair of slots 14 in the skin 11. Slots 14 permit a belt 19 to pass through said slots 14, and about the reinforcements 18, so as to tie about a tent stake 21 as shown in FIG. 4 and FIG.

5. A pair of curved clamping fingers 16 are mounted directly above the reinforcements 18 near the top edge 17 of the device, so as to fasten about a tent rope 22 which may be anchored to the tent stake 21.

The outer surface of the device 10 is grooved with an external axial recess 15 which is shaped and located so as to receive the internal protrusions of the reinforcements 18 and rope clamps 16 of a second stake guard 10 which may be stacked over the device in the storage

mode.

As shown in FIG. 4, the device may be employed about a tent stake 21 which rises considerably above the ground level 25 and about the attached stake rope 21 which wraps about the stake 21 and passes through the axial slot 12 of the stake guard. Alternately, as shown in FIG. 5, the device may be employed about a tent stake 21 which rises just above the ground level 25, with the attached stake rope 22 rising vertically through the clamp fingers 16 of the device.

When fastened as shown in either FIG. 4 or FIG. 5 to a tent stake 21, the device 10 serves as a visual warning to protect against a passerby tripping over the stake rope or the stake itself. The use of a plastic or rubber compound as the base material further acts as a safeguard against injury to a passerby who accidentally rubs against the device.

Since obvious changes may be made in the specific embodiment of the invention described herein, such modifications being within the spirit and scope of the invention claimed, it is indicated that all matter contained herein is intended as illustrative and not as limiting in scope.

Having thus described the invention, what I claim as new and desire to secure by Letters Patent of the United States is:

1. A guard device for shielding a tent stake and attached stake anchor rope so as to prevent injury to a passerby who might otherwise walk into, or trip over the stake or stake rope, said guard device calling visual attention to the attached tent stake or stake anchor rope, comprising

a hollow conical member formed of a plastic composition which is adaptable for fitting over a tent stake, said member being formed with a continuous slot which runs from the top edge to the bottom edge of the member, and

means to fasten a strap to the inside face of the member so as to strap the inside face of the member to a tent stake.

2. The combination as recited in claim 1 together with slotted clamping means on the inside face of the member so as to clamp the inside face of the member to a rope which may be fastened to the tent stake to which the member is fastened.

3. The combination as recited in claim 2 together with recesses formed in the external face of the member, said recesses being of a size and shape to fit about the internal protrusions of a similarly shaped device which is stacked about the described device.

4. The combination as recited in claim 3, the outer surface of which is coated with a light reflective substance.

5. The combination as recited in claim 3 which is formed of a plastic material which incorporates material of fluorescent-producing properties.

6. The combination as recited in claim 3, the outer surface of which is coated with a fluorescent substance.
